COOLED SEALER FOR WRAPPING MACHINES

Donald M. Fincke, Great Neck, N. Y., assignor to
American Machine & Foundry Company, a corporation of New Jersey

Application January 27, 1937, Serial No. 122,519

2 Claims. (Cl. 93—2)

This invention relates to a machine for sealing the seams of the wrappers which envelop such articles as loaves of bread; especially to a machine designed to heat locally the seams of a wrapper coated or impregnated with a substance adapted to soften when heated, and to be self-sealing cohesively when thereafter chilled; and more particularly to such a machine in which sealing elements are provided with ducts for the circulation of a cooling fluid through said elements.

Conventional sealing machines of the above class are subject to the inconvenience that a vaporous refrigerant is circulated in the ducts of the sealing elements, and, as known to those skilled in the art, such a system is apt to leak and thus put the machine out of commission. This unfavorable condition is aggravated when adjustments of the sealing elements are provided for, inasmuch as the use of a flexible conduit for the vaporous refrigerant is not satisfactorily vapor-tight, especially under rigorous operating conditions.

Bearing the above problem in mind, the general object of the present invention is to provide a sealing machine of the class described with a sealer unit comprising sealer elements suitably disposed for direct sealing contact with the article to be sealed, and have ducts for the circulation of cooling liquid, such as brine, which may be refrigerated by an ammonia or other suitable system at a convenient distance from the sealing station to avoid entirely the disadvantages above recited; the use of brine, for example, as a cooling liquid, making it possible to use suitable flexible connections, and thus to secure optimum adjustability of the sealing elements.

Another object of the invention is to provide a wrapping machine having such a cooled sealer with a refrigerating mechanism which comprises a self-contained refrigerator system mounted on a separately formed frame or carriage by which the refrigerator is constituted a self-contained unitary structure movable readily into operative juxtaposition with any wrapping machine or a battery of such wrapping machines. It is thus possible, when any refrigerating unit gets out of order, to substitute a reserve unit which has been left in order for such substitution. Accordingly, expensive delays are eliminated and the continuity of operation of the wrapping machines is assured.

Still another object of the invention is to provide for the combination with a wrapping machine of the class described having a seal-heater

element, and with a cooled sealer connected with said wrapping machine, of a self-contained refrigerator unit adapted to be assembled in operative relation with said wrapping machine at the delivery end of the sealer mechanism, for receiving from said heater element the sealed articles.

Still another object of the invention is to provide complementary belt conveyors, embracing the tops and bottoms of the loaves with yielding pressure, and at the region thereof between the ends of the loaves, so that only the loaf-ends are engaged directly with the sealing elements, and are carried positively along them in sealing contact.

A cognate object is to complete the bottom seal during a dwell in the travel of each loaf after it is discharged by the belts from the run between the end-sealing elements.

Other objects and advantages of the invention will appear as the particular physical embodiment of the invention selected for illustration and description thereof progresses.

In describing the invention in detail, and the particularly physical embodiment selected to illustrate the invention, reference will be had to the accompanying drawings and to the several views thereof, in which like characters of reference designate like parts throughout the several views, and in which:

Fig. 1 is a partial side elevation of an end of a wrapping machine showing in assembly therewith a cooled sealer and a mobile refrigerating unit in the construction of which the present invention has been embodied;

Fig. 2 is a side elevation of the refrigerator unit;

Fig. 3 is a schematic view showing the hook-up of the refrigerator unit with the sealing unit;

Fig. 4 is a fragmentary detail view in vertical sectional elevation taken on the line 4—4 of Fig. 1; and

Fig. 5 is a fragmentary detail view in vertical sectional end elevation taken on the line 5—5 of Fig. 1.

Referring to Fig. 1, the supporting rods 10 of the wrapping machine, at one end, are supported in bearings 11 and, at their other end, in legs 11a. A U-shaped hanger 12 attached at the end of the rods 10 supports one end of the bars 13 which project from the wrapping machine frame. Rods 10 carrying bearings 14, 15, and 16 which support a bar 17 and spindles 18 and 19, respectively. The spindles 18 and 19 are equipped at both ends with arms 20 and 21, respectively, connecting to bars 22 carrying the side tanks 23 which engage

and seal the ends of the package. The bar 17, at its ends, carries brackets 24 which support a driven conveyor shaft 25. A pulley 26, mounted on shaft 25, driving a conveyor belt 27 runs over an idler pulley 28 loosely mounted on a shaft 29, the ends of said shaft being carried by adjustably mounted arms 30 which are guided in the slotted portion of take-up brackets 31 attached to rods 10. In the space between the pulleys 26 and 28 is placed a support plate 32, preventing sagging of the upper loop of conveyor 27, carried by holders 33 attached to the rods 10.

The bottom tank 34, which is carried by arms 30, seals the bottom seam of the packages as they are conveyed over the same. The packages are then pushed over a bridge 35 onto a cover 36, of the refrigerator unit (see Figs. 1 and 2) from which they are taken off by the operator.

A driven shaft 40, of the wrapping machine, is provided with a sprocket 41 driving, by means of a chain 42, a sprocket 43 mounted on a shaft 44 carried by a U arm 45 adjustably supported on shaft 40. A small sprocket 46 also mounted on shaft 44, by means of a chain 47, drives a sprocket 48 attached to a shaft 49 of the top tension belt mechanism. Shaft 44 is provided with a pair of loosely mounted arms 50, Fig. 4, at their other end having an elongated slot 51 receiving a stud 52 carried by arms 53 supporting the shaft 49. The arm 45 pivotally mounted on shaft 40, together with the pivotal mounting of arms 50 and 53, permits a vertical up and down adjustment of the top tension belt mechanism to suit the height of the package, by means to be later described.

On shaft 49 is mounted a pulley 55 driving a top tension belt 56 running over a pulley 57 carried by a shaft 58 supported in take-up blocks 59 adjustably attached to U shaped longitudinal strips 60 (Figs. 1 and 5). Members 60 carry angular frames 61 and 62, the former being equipped with studs 63 supporting a plate 64 engaging the under loop of belt 56 and the frame 62 is provided with a vertical spindle 65 engaging in a hub of a tie bracket 66 spanning the bars 13. A similar tie bracket 61, also spanning said bars, guides a vertical spindle 68 equipped with a hand wheel 69. The manipulation of hand wheel 69, by means of a sprocket 70 on spindle 68, turns a sprocket 71 on spindle 65, through chain 72, whereby the belt 56 may be raised or lowered to best suit the height of the packages being wrapped, thus applying a gentle pressure to the package and assuring a well sealed bottom seam.

Referring to Fig. 3, the bottom coils of condenser 75 and the receiver 76 contain a liquid refrigerant. The upper coils of the condenser contain a refrigerant gas under sufficient pressure to prevent the liquid refrigerant from boiling or vaporizing. The gas pressure pushes down upon the liquid forcing the liquid up through the feed tube 77 leading to an expansion valve 78 regulating the flow of liquid and permitting only a small amount of liquid to rush into the cooling coils. The cooling coils, Figs. 2 and 3, consist of a plurality of inner coils 79 and a plurality of outer coils 80, the liquid flowing through expansion valve 78 into the inner coils 79 and coils 80. The aforementioned coils are submerged in a supply brine solution, constituting a permanently liquid or non-gaseous refrigerating medium, stored in a tank 81 of the housing 82. The tank 81 is surrounded at its sides and bottom with insulating pads 83, and the top cover 36 carries an insulating pad 84.

A motor 85, which is independently controlled from the rest of the unit, is mounted on a bracket 86 and drives a pump 87 circulating the brine solution entering through a port 88 provided in the tank 81. The pump forces the solution through a tube 90 leading to a T 91 where the solution branches into a tube 92 feeding one of the side tanks 23 and into a tube 93 feeding the other side tank 23, the solution then flowing through the chambers within said tanks and discharging into tubes 94 and 95 directing the flow of the solution into the bottom tank 34. The flow of the solution passes through the bottom tank, returning to the storage tank 81 by means of a tube 96 attached to the bottom tank.

When the temperature of the brine in tank 81 rises above the predetermined point, a thermostatic bulb 100 and capillary tube 101 of remote type acts upon a switch 103 which starts a compressor. The gas with which the thermostatic element is charged is very sensitive to temperature changes. A rise in temperature at the bulb 100, Fig. 3, which is submerged in the brine solution, communicates through the capillary tubing 101 to a pressure control unit 102 of a conventional type; therefore, a brief description of the same is deemed sufficient. A rise in temperature at the bulb 100 is accompanied by a corresponding rise in gas pressure which acts upon the control unit 102, which through suitable linkage tilts a mercury switch 103 to an on-position, as the temperature of the bulb and gas within it drops, this being accompanied by a drop in gas pressure which acts upon said linkage of the control unit and reverses the action of the same, 35 tilting the mercury switch to an off-position.

When the mercury switch 103 is tilted to its on-position, the flow of current from the line wires 104 passes through a throw switch 105, normally in closed position, and through wires 106 and 107 thereby starting a motor 108. The motor 108 in starting drives a belt 109 which sets a compressor 110 in motion, whereby through a pipe 111 connecting to the coils 79 and 80, the gas is pumped out of said coils and returned to the compressor where it is compressed. A draft of air sent over the condenser coils 75 by means of a fan (not shown) attached to the motor shaft hastens the process of cooling the liquid refrigerant. When the temperature again drops, the mercury switch 103 will be tilted to its off-position, thus stopping the motor.

The packages have been wrapped and their ends folded by suitable means (not shown) are pushed across a bottom-sealing plate 115, Fig. 1, and between a set of side heater members 116, whereby the bottom and end flaps of the packages are sealed. The members 116 are carried by adjustable brackets (not shown) mounted at each end of the package runway, permitting in and out adjustment of the sealers 116 to suit the length of the packages being wrapped, the same brackets each carrying an arm 117 provided with a comb-like member 118 which guides the packages across the gap between the heated sealers 116 and the frigid sealers 23. The air gap between said sealers is great enough to arrest the heat from radiating to the frigid sealers thus preventing defrosting of the same. The advancing package finally reaches the conveyor belt 27 which transports the same past the frigid side tanks 23 which contact the hot seals of the end flaps of the package, thus setting the same. In passing through the cooling chamber the package is subjected to a gentle pressure between 75

conveyor 27 and top tension belt 56, thereby assuring a well closed bottom seal. The package in issuing from the cooling chamber comes to rest on the frigid bottom sealer 34 which sets the hot bottom seal, the package remaining on member 34 until the succeeding package pushes it onto the take-off cover 36. In this manner it is seen that the end and bottom seams of the package are perfectly set, thus assuring an air-tight and neat appearing wrapped package.

The turning of a handle 120 attached to the end of spindle 18 turns a sprocket 121 over which runs a chain 122 turning a sprocket 123 mounted on spindle 19. This arrangement permits in and out adjustment of the frigid side tanks to suit the length of the package.

What is claimed is:

1. In a wrapping machine, the combination with a cooling unit comprising cooling elements in the form of closed metal tanks adapted to receive a supply of cooling liquid and suitably disposed for direct contact with the ends of heat sealed packages to congeal the heated seals thereof, means relatively remote from said unit for refrigerating a supply of cooling liquid and circulating it through said tanks, a pair of endless traveling belts disposed to admit packages therebetween and coating to grip the top and bottom thereof and advance them sidewise past

said tanks with their ends contacting the latter, a device for relatively moving said belts toward and away from each other to admit packages of various heights therebetween, and mechanism for driving said belts in the various adjusted positions thereof.

2. In a wrapping machine, the combination with a cooling unit comprising cooling elements in the form of closed metal tanks adapted to receive a supply of cooling liquid and suitably disposed for direct contact with the ends of heat sealed packages to congeal the heated seals thereof, means relatively remote from said unit for refrigerating a supply of cooling liquid and circulating it through said tanks, a pair of endless top and bottom traveling belts disposed to admit packages therebetween and coating to grip the top and bottom thereof and advance them sidewise past said tanks with their ends contacting the latter, a device for moving said top belt toward and away from the bottom belt to admit packages of various heights therebetween, mechanism for driving said belts in the various adjusted positions thereof, a member for yieldingly pressing the active run of the top belt into engagement with the packages, and means for adjusting said member to compensate for adjustment of the top belt.

DONALD M. FINCKE.
